UNITED STATES PATENT OFFICE

2,443,834

SOUND-OPERATED TOY

Harry W. Noyes, West Haven, Conn.

Application June 13, 1946, Serial No. 676,544

1 Claim. (Cl. 46—145)

1

This invention relates to an improvement in sound-operated toys, that is, a toy which is operated by the action of sound upon a vibratory surface, and particularly to toys operated by breaking an electric current.

The object of this invention is to provide a simple and attractive toy, including a movable object which is propelled by a spring-actuated lever, which lever is released by breaking a circuit through a battery and an electromagnet by the action of sound.

With the above and other objects in view, as will appear to those skilled in the art from the present disclosure, this invention includes all features in the said disclosure which are novel over the prior art.

In the accompanying drawings, in which certain modes of carrying out the present invention are shown for illustrative purposes:

Fig. 1 is a front view of the toy;

Fig. 2 is a side view of the same;

Fig. 3 is a side view, on a larger scale than Fig. 2, with a portion of the side wall broken away;

Fig. 4 is a sectional view on the line 4—4 of Fig. 3;

Fig. 5 is a perspective view of the switch-bracket, detached; and

Fig. 6 is a perspective view of the switch.

For the purpose of illustration, the housing 10 is the representation of a fire-department house with a front doorway 11. One side wall 12 of the housing is formed from a thin piece of plywood or other suitable material, to act as a sounding board.

Near the top of the rear wall 13 and secured thereto, is a bracket 14 in which is mounted an operating-lever 15 which extends downwardly in front of an electromagnet 16 which is also mounted on the rear wall 13.

The upper end of the lever 15 extends above the bracket 14 to form an arm 17 to which is attached a spring 18, the lower end of which is secured to the said rear wall 13 above the magnet 16. The bracket 14 is formed with a finger 19 with which the spring 18 will contact when the lever 15 is released. Also mounted on the rear wall 13 between contacts 20 and 21, is a battery cell 22 which is held in place by a clip 23.

Secured to the outside of the side wall 12 is a

2

switch-bracket 24 on which is hung a switch 25 having a lip 26 at its lower end to contact with the ends of wires 27 and 28 which extend through the side wall 12. The wire 27 extends into connection with the upper end of the battery cell 22 through the contact 20, and the wire 28 extends into contact with the lever-bracket 14 and hence is in electric contact with the lever 15. The end of the magnet wire 29 extends into contact with the lower end of the battery cell 22 through the contact 21.

Supported by a bracket 30 secured to the inside of the front wall 31, above the doorway 11, is a bell 32 in position to be struck by a hammer 33 suspended from a transverse rod 34 in the path of movement of the lever 15.

On the floor 35 are guideways 36 and 37 to direct a wheeled toy 38, here representing a piece of fire-department apparatus, the rear end of 20 which is adapted to move the lever 15 into contact with the electromagnet 16 and so close the circuit.

When thus arranged, a shout or concussion directed toward the face of the side wall 12 will cause that wall to vibrate sufficiently to jar the switch 25 out of contact with the wires 27 and 28, or either of them, and so break the circuit and release the lever 15 from the magnet 16 and allow it to move forwardly under the action of the spring 18 and thus eject the toy. At the same time, the lever 15 will hit the bell-hammer 33 and throw it against the bell 32.

As the spring 18 acts to move the lever 15 forward, it comes in contact with the lip 19, thus 35 momentarily arresting the tension in that direction on the lever, allowing the said lever to swing slightly backwardly again extending the spring, and to again be thrown forwardly against the hammer 33, to cause the bell to again sound.

40 The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claim are intended to be embraced therein.

I claim:

50 The combination with a housing having a vibra-

factory side panel; an electromagnet; a battery; an electrically-controlled spring-actuated operating-lever; circuit wires exposed through the said panel; a switch connecting said circuit wires and adapted to be moved out of contact therewith by the vibration of said panel; a toy positioned to close an electric circuit by moving said lever into contact with said electromagnet and to be ejected by said lever when the circuit is broken; a bell and a bell-hammer being operated by the movement of said lever; and a bracket formed

with a finger to contact with the said spring, whereby the action of said spring is checked.

HARRY W. NOYES.
